UNITED STATES PATENT OFFICE.

JAMES L. CRANE, OF CLEVELAND, OHIO, ASSIGNOR TO THOMAS J. CRANE,
OF CLEVELAND, OHIO.

SHOW-FRONT OR SHOW-CASE.

SPECIFICATION forming part of Letters Patent No. 745,158, dated November 24, 1903.

Application filed May 15, 1903. Serial No. 157,211. (No model.)

To all whom it may concern:

Be it known that I, JAMES L. CRANE, a citizen of the United States of America, residing at Cleveland, in the county of Cuyahoga and State of Ohio, have invented certain new and useful Improvements in Show-Fronts or Show-Cases; and I hereby declare the following to be a full, clear, and exact description of the invention, such as will enable others skilled in the art to which it pertains to make and use the same.

My invention relates to improvements in store-fronts or show-cases, and pertains more especially to their corner construction.

15 The object of this invention is to provide a meritorious construction and arrangement of parts in fastening together two vertically-arranged glass plates which are arranged at an angle to each other at their adjacent vertical edges without necessitating more than the notching or recessing of only one of the said edges and without interfering with the abutting of the said edges against each other.

20 With this object in view my said invention consists in certain features of construction and combinations of parts hereinafter described, and pointed out in the claims.

25 In the accompanying drawings, Figure 1 is an exterior view of a show-front or show-case embodying my invention. Fig. 2 is a horizontal section on either one of lines 2 2, Fig. 1. Fig. 3 is a horizontal section on either one of lines 3 3, Fig. 1. Figs. 2 and 3 show the parts full size. Fig. 4 is a vertical section on line 30 4 4, Fig. 2, looking in the direction indicated by the arrow. Fig. 5 is a view in perspective of one of the corner-fasteners detached.

35 Referring to the drawings, A and B designate two vertically-arranged or upright glass plates of a store-front or show-case, which are arranged at an angle to each other. The said plates A and B at their adjacent vertical or upright edges are correspondingly beveled and tightly fitted together, so that the said 40 edges abut against each other and form a tight joint, preventing the ingress of dust and dirt from without to and between the said edges.

To positively retain the plates A and B in their relative position, I employ corner-fasteners D, arranged at different elevations, re-

spectively, between the upper and lower ends of the plates. Each corner-fastener D comprises an outer angle-iron or corner-iron or corner-piece D', an inner angle-iron or corner-piece D², and means instrumental in connecting the two corner-pieces D' and D² together. The outer corner-piece D' of each corner-fastener is arranged outside the angle formed by the plates A and B and around the outer corner of the said plates has two arms 55 or wings d and d', arranged to engage or bear against the outer side of the different plates A and B, respectively. The inner corner-piece D² of each corner-fastener is arranged within the angle formed by the plates A and B and has two arms or wings d² and d³, arranged to engage or bear against the inner side of the different plates A and B, respectively.

60 In the construction illustrated the connection between the corner-pieces D' and D² of each corner-fastener comprises a stud-bolt E, which is screwed at its inner end into a correspondingly screw-threaded hole F, with which the outer corner-piece D' of the said 65 fastener is provided at its inner side and between the arms or wings d and d' of the said corner-piece. The bolt E of each corner-fastener extends inwardly from the outer corner-piece D' of the said fastener to and loosely 70 through a hole K, formed in and extending through the inner corner-piece D² of the said fastener. The said bolt, in order to necessitate only the recessing or notching of one of the adjacent upright edges of the plates A 75 and B in accommodating the location of the said bolt, is notched or recessed, as at e, at its side which faces the unrecessed of the said edges. It will be observed, therefore, that one of the plates A and B and plate B 80 of the show-front or show-case illustrated is recessed or notched, as at b, transversely of its edge at the corners formed by the said plates to accommodate the location of the aforesaid bolt, which extends through the 85 notch or recess b, and that the said bolt is cut away or recessed, as hereinbefore described, to avoid the necessity of recessing or notching the plate A. Hence by my invention one of the plates hereinbefore described 90

as being placed in position at an angle to each other need not be notched or recessed at the adjacent upright edges of the said plates to accommodate the location of the bolt or connection between the corner-pieces of a corner-fastener employed in holding the said plates in position.

A corner-fastener D is shown detached in Fig. 5.

- 10 The means employed for effecting the required connection between the bolt E and the inner corner-piece D² of each corner-fastener comprises a nut G, mounted on the free end of the bolt and coöperating when tightened relative to the said corner-piece with the bolt in holding or retaining both corner-pieces of the said fastener in their operative position, wherein they bear against or engage the plates A and B.
- 20 I would have it understood that my invention is not limited to the hereinbefore-described details of construction employed in holding the two corner-pieces of a corner-fastener in their operative position, but embracing, broadly, any connection between the said corner-pieces extending between the outer corner and inner corner formed by and between the said plates A and B and where it extends between the said corners being arranged entirely within a notch or recess formed in one of the said plates only.

What I claim is—

1. In a corner construction for show-windows, show-cases, &c., the combination of two plates arranged at an angle to each other, one of said plates having a notch therein; an angle-iron arranged around the outer corner of said plates; a bolt extending from said angle-iron through the notch in said plate, the body of said bolt being arranged entirely within the notch in one of said plates; an inner angle-iron and means for connecting said bolt therewith.

2. In a corner construction for show-windows, show-cases, &c., the combination of two plates arranged at an angle to each other, one of said plates being notched at the corner; a corner-iron arranged around the outside of the plates; a bolt extending from said angle-iron through said notch, said bolt being notched at one side; an angle-iron arranged within the angle; and means for connecting the bolt therewith.

3. The combination, with two upright glass plates placed in position at an angle to each other, with one of the adjacent upright edges of the said plates provided with a notch or recess, of a corner-fastener comprising an outer corner-piece arranged around the outer corner of the said plates, an inner corner-piece arranged within the aforesaid angle adjacent the inner corner formed by the said plates, and a connection between the said corner-pieces extending between the aforesaid corners, which connection comprises a bolt extending inwardly from the outer corner-piece to and extending loosely through

the inner corner-piece, which bolt, where it extends between the aforesaid corners, is arranged, at one side, entirely within the aforesaid notch or recess in one of the aforesaid plates, and cut away at its opposite side to avoid recessing or notching of the other of the said plates, and a nut mounted on the bolt.

4. The combination, with two upright glass plates placed in position at an angle to each other, with one of the adjacent upright edges of the said plates provided with a notch or recess, of a corner-fastener comprising an outer corner-piece arranged around the outer corner of the said plates, an inner corner-piece arranged within the aforesaid angle adjacent the inner corner formed by the said plates, and a connection between the said corner-pieces extending between the aforesaid corners, which connection comprises a bolt projecting inwardly from the outer corner-piece to and extending loosely through the inner corner-piece, which bolt, where it extends between the aforesaid corners, is arranged entirely within the aforesaid notch or recess, and means for securing the corner-pieces in their operative position.

5. The combination, with two upright glass plates placed in position at an angle to each other, with one of the adjacent upright edges of the said plates provided with a notch or recess, of a corner-fastener comprising an outer corner-piece arranged around the outer corner of the said plates, an inner corner-piece arranged within the aforesaid angle adjacent the inner corner formed by the said plates, and a connection between the said corner-pieces extending between the aforesaid corners from the outer corner-piece inwardly to and through the inner corner-piece, and, where it extends between the corners, being arranged entirely within the aforesaid notch or recess.

6. The combination, with two upright glass plates placed in position at an angle to each other, with their adjacent upright edges abutting against each other and with one of the said edges provided with a transverse notch or recess, of a corner-fastener comprising an outer corner-piece arranged to bear against the outer sides of the aforesaid plates adjacent the outer corner of the said plates, an inner corner-piece arranged to bear against the inner sides of the said plates adjacent the inner corner formed by the said plates, and a connection between the said corner-pieces extending between the aforesaid corners, and, where it extends between the corners, being arranged entirely within the aforesaid notch or recess.

7. The combination, with two upright glass plates placed in position at an angle to each other, with one of the adjacent upright edges of the said plates provided with a notch or recess, of a corner-fastener comprising an outer corner-piece arranged around the outer corner of the aforesaid plates, an inner cor-

ner-piece arranged at the inner sides of the said plates adjacent the inner corner formed by the said plates, and a connection between the said corner-pieces extending between the 5 aforesaid corners and, where it extends between the said corners, being arranged entirely within the aforesaid notch or recess.

8. The combination, with two upright glass plates placed in position at an angle to each 10 other with one of the adjacent upright edges of the said plates provided with a notch or recess, of a corner device arranged at the outer corner of the aforesaid plates, an inner corner device arranged at the inner sides of said 15 plates adjacent the inner corner formed by the said plates, and a connection between the said corner devices extending between the aforesaid plates, which connection where it extends between said plates being arranged 20 within the aforesaid notch or recess in the

notched or recessed plate and entirely exteriorly of the other plate.

9. The combination with two glass plates arranged at an angle to each other, one of the plates having a notch or recess in its edge 25 which is adjacent to the other plate, and a corner-fastener comprising an outer corner device, an inner corner device and a connection between said corner devices, which connection extends through the notch or recess 30 in the notched or recessed plate and arranged entirely exteriorly of the other plate.

In testimony whereof I sign the foregoing specification, in the presence of two witnesses, this 7th day of May, 1903, at Kansas City, 35 Missouri.

JAMES L. CRANE.
